UNITED STATES PATENT OFFICE.

HARRIET N. LEGAN, OF DENVER, COLORADO.

HOOK AND EYE.

No. 902,746.

Specification of Letters Patent.

Patented Nov. 3, 1908.

Application filed October 12, 1907. Serial No. 397,154.

To all whom it may concern:

Be it known that I, HARRIET N. LEGAN, a citizen of the United States of America, residing at Denver, in the county of Denver and State of Colorado, have invented certain new and useful Improvements in Hooks and Eyes, of which the following is a specification.

This invention relates to new and useful improvements in hooks and eyes and more particularly in the hook and eye shown and described in my United States Patent No. 860,039, issued July 16 1907.

The object of the present invention is to provide the coöperative fastening members with separate appliances which, when in place, secure and house the pin points, which firmly connect the parallel shanks of each member and prevent their separation; which aid in retaining the engaging portions of the two members in the interlocked position and which furthermore simplify the construction and in consequence lessen the cost of manufacture of the article. I attain this object by the means illustrated in the accompanying drawings in the various views of which like parts are similarly designated and in which

Figures 1 and 3—represent respectively a plan and side view of the eye member, Figs. 2 and 4—respectively, a plan and side view of the hook member comprised in my invention, Figs. 5 and 7—respectively, a plan and side view of a modified construction of the eye member, Figs. 6 and 8—similar views of a modified construction of the hook member, Fig. 9—an enlarged cross section taken along a line 9—9, Figs. 3 and 4, Fig. 10—an enlarged side view of the guard-forming link, Fig. 11—an underneath view thereof, and Figs. 12 and 13—respectively a side view and an underneath view of a modified construction of the link.

Both the hook member and the eye member are produced by bending a doubled piece of wire and respectively comprise an engaging portion 6 and a fastening element 7, the latter being identical in the two members and composed of two identical parallel members 5 each of which comprises a shank 8 which connects with the engaging portion, a pin 11 which extending below and in approximate parallel relation to the shank, terminates in proximity to the said engaging portion and a spring loop 10 intermediate the shank and the pin.

The engaging portion 6 of the hook mem-

ber is shaped to form a hook 12 and that of the eye member is produced by bending the middle portion of the wire in the form of a loop 13.

The portions of the doubled wire in the hook 12 extend parallelly in close proximity to each other and are separated at the points of junction of the hook with the two shanks 8, as illustrated in the drawings.

Instead of being connected by the coil 10, the shanks and pins may be brought in their relative positions by a single bend 9, as shown in Figs. 5 to 8 inclusive, which modified form is by reason of its simplicity, especially suited to the manufacture of the smaller sizes of my improved hooks and eyes.

At the points of junction of the engaging portion of each member with the respective shanks 8, I apply a link 14, which is composed of a flat strip of pliable metal, the ends of which are bent down and inwardly and curved at their extremities to form guards 15 for the reception of the points of the pins 11.

Each link is furthermore formed at the points of junction of its middle portion 16 and the downwardly ranging guards, with transversely disposed sleeves 17, designed to admit and engage the shanks 8 of the hook or eye to which the link is applied and which are produced by cutting the ends of the article with a U-shaped tool and curving the cut-out portions inwardly, towards the under-surface of the said middle portion.

In the modified form of the link illustrated in Figs. 12 and 13, the downwardly extending ends of the link are divided by a central cut and the portions 18 and 19 curved inwardly to respectively form the pin guards and the fastening sleeves.

The links are attached to the hook or eye by placing the flat shank 16 upon the upper surface of the shanks 8 at the juncture of the latter with the engaging portion 6 and bending the sleeves 17 around the said shanks, substantially as shown in Fig. 9 of the drawings.

The shanks 8 being thus connected, are firmly held against lateral displacement and the guards formed by the downwardly ranging, inwardly curved ends of the link are well adapted to house and shield the points of the pin 11 so as to retain them in their position on the garment and to prevent possible injury to the wearer.

It will be observed that in addition to its other uses, the shank 16 of the link on the

hook member, being disposed below the engaging portion 6, forms a safeguard against accidental unlocking of the eye member when the two members are in the interlocked position.

Having thus described my invention what I claim is:—

A member of a hook and eye fastener comprising an engaging portion, parallel shanks 10 extending therefrom, pins connected with the extremities of the shanks and terminating adjacent to the said engaging portion and a link whose middle portion extends over the shanks adjacent the engaging portion and

whose ends are cut to form sleeves which 15 clampingly surround the shanks and guards which extend parallel to the said sleeves and on the same side of, but at greater distance from, the said middle portion to receive and shield the points of the pins when the latter 20 are substantially parallel to the shanks.

In testimony whereof I have affixed my signature in presence of two witnesses.

HARRIET N. LEGAN.
